UNITED STATES PATENT OFFICE.

HARRY R. HOLBROOK, OF ATTLEBORO, MASSACHUSETTS.

VENDING-MACHINE.

No. 879,546.

Specification of Letters Patent.

Patented Feb. 18, 1908.

Application filed September 19, 1904. Serial No. 224,938.

To all whom it may concern:

Be it known that I, HARRY R. HOLBROOK, a citizen of the United States, residing at Attleboro, in the county of Bristol and State 5 of Massachusetts, have invented a new and useful Improvement in Vending-Machines, of which the following is a specification.

This invention has reference to an improvement in vending machines and more 10 particularly to an improvement in automatic vending machines from which the article is automatically delivered to the buyer on the dropping of a coin through a coin slot in the machine.

15 Vending machines having a series of automatically controlled merchandise delivery hoppers have been used. This construction is complicated, expensive to manufacture, and detrimental, as the buyer is liable to 20 drop the coin in the wrong slot.

25 The object of my invention is to control a series of automatically-operated merchandise delivery hoppers from one coin slot and chute, and I accomplish this object by rotatably securing the hoppers about a central coin chute which is operatively connected in succession with each hopper by revolving the hoppers around the coin chute.

30 A further object of my invention is to improve the construction of an automatic vending machine, whereby the merchandise to be vended is displayed to better advantage and a more attractive vending apparatus is constructed than has heretofore been 35 done.

My invention consists in the peculiar and 40 novel construction of an automatic vending machine having a hollow base in which is a coin receptacle and an open compartment through which the merchandise is delivered, a hollow central column supported in and 45 extending upwards from the base, a coin chute adapted to be reciprocated in the central column, a series of vertical merchandise delivery hoppers secured at their ends in a circle to disks which are rotatably secured to the central column, a glass cylinder surrounding the hoppers and central column and held in position by the disks, an ornamental top supported on the upper end of the central column and having a coin slot coinciding with the upper end of the coin chute, means for revolving the disks, hoppers and glass cylinder around the central column and coin chute, mechanisms on the hoppers adapted to engage in succession

with mechanism on the coin chute, whereby on the dropping of a coin through the coin slot and chute the mechanism is operated to automatically deliver one piece of merchandise, such as a collar button, to the open compartment in the base, means for automatically holding the hoppers in succession over the open compartment, means for locking the hoppers in their delivery position over the open compartment when a coin is inserted in the coin slot and for locking the coin slot against the insertion of a coin when a hopper is in an inoperative position, thereby preventing the machine from receiving a coin without delivering the merchandise, and other details of construction as will be more fully set forth hereinafter.

Figure 1 is a vertical sectional view taken centrally through my improved automatic vending machine, showing the automatic mechanism in the normal position. Fig. 2 is a transverse sectional view taken on line X X of Fig. 1 with the top having the coin slot removed. Fig. 3 is a transverse sectional view taken on line Y Y of Fig. 1 looking toward the base, and Fig. 4 is an enlarged detail vertical sectional view taken centrally through the central supporting column and one of the merchandise delivery hoppers, showing the automatic mechanism in its normal position in full lines, in the position it would assume when a coin enters the coin slot to set the mechanism in light broken lines, and in the final position of the mechanism which is assumed by the dropping of the coin in the coin chute to deliver the merchandise, in heavy dotted lines.

In the drawings, *a* indicates the base, *b* the hollow central column, *c* the coin chute, *d* the lower supporting disk, *e* the upper disk, *f* the merchandise delivery hoppers, *g* the glass cylinder, *h* the cylinder retaining cap, *i* the ornamental top of the machine, *k* the collar buttons, and *l* a coin shown in broken lines to illustrate the operation of my improved automatic vending machine.

The hollow base *a* has the central hub *a'* which supports the central column *b* and extends upwards from the top of the base to form a bearing for the lower disk *d*, the delivery compartment *a²* having the inlet opening *a³* in the top of the base and the outlet opening *a⁴* in the side of the base, the open top chamber *a⁵* in the top of the base in which is an automatic spring actuated stop or holding device consisting of the coiled

spring a^6 , the plunger a^7 , the ball stop a^8 , and the coin receptacle a^9 secured in the base by the screws $a^{10} a^{11}$, as shown in Fig. 1.

The central column b is in the form of a circular tube the lower end of which is firmly secured in the hub a' in the base and has the opening b' , the aperture b^2 , and the slot b^3 in the side facing the compartment a^2 .

The coin chute c in the column b is constructed from sheet metal in the form of a deep U-shaped trough the sides $c' c'$ and the bottom c^2 of which guide the coin. The curved upper end c^3 of the chute extends outwardly through the slot b^3 in the column b and has the bent-over teats $c^4 c^4$ bearing on the outside of the column b to hold the chute in its operative position, as shown in Figs. 2 and 4. The release lever c^5 is shaped to form a continuation of the coin chute c . It is pivotally secured to the lower end of the chute by the pin c^6 and is held inwardly at an angle by the light coiled spring c^7 which is secured to the release lever and to the lower end of the chute. The lower end of the release lever c^5 has the projecting stop arms $c^8 c^8$ and the outwardly-bent L-shaped end c^9 which enters the opening b' in the column b . The slide c^{10} is secured to the lower end of the coin chute c by the pivot pin c^6 . The upper end c^{11} of the slide acts as a stop against the upper end of the aperture b^2 in the column b and the lower end c^{12} extends downward on the outside of the column, as shown in Fig. 4. The coin chute c is held in its upward or normal position by the coiled spring c^{13} secured to the slide c^{10} and to the column b .

The lower disk d has the central hole d' through which the column b extends, the series of radial openings $d^2 d^2$ through which the merchandise or collar buttons $k k$ are delivered, the rim d^3 for holding the glass cylinder g in place, and the knobs $d^4 d^4$ on the rim for revolving the disk around the column b , as shown in Figs. 3 and 4.

The upper disk e has the central hole e' for the column b , and the series of radial openings $e^2 e^2$ for supplying the hoppers $f f$ with the collar buttons $k k$, as shown in Figs. 1 and 4.

The hoppers $f f$ are in the form of a flattened tube, each tube having the central longitudinal slot f' in its outer face, the lower aperture f^2 and the upper opening f^3 in the back, the projections $f^4 f^4$ on the ends of the tube, and the ears $f^5 f^5$ and $f^6 f^6$ on the back. The latch f^7 is pivotally secured near its center to the ears $f^5 f^5$ by the pin f^8 and has the hook-shaped lower end f^9 adapted to enter the aperture f^2 , the ears $f^{10} f^{10}$ on its upper end, and the yoke f^{11} extending outward from the pivot toward and under the slide c^{10} . The operating lever f^{12} has the notched finger f^{13} adjacent its upper end which enters the opening f^3 , the lower end f^{14} which extends downward through the

yoke f^{11} into a position for the L-shaped end c^9 on the release lever c^5 to engage with it and is pivotally secured to the upper end of the latch f^7 by the pin f^{15} which passes through the ears $f^{10} f^{10}$ on the latch and the finger f^{13} 70 on the operating lever. The flat spring f^{16} is secured to the back of the hopper by the ears $f^6 f^6$, its free end bearing on the upper end of the operating lever f^{12} , as shown in Fig. 4. 75

The cylinder retaining cap h has the annular lip h' which extends downward over the upper end of the glass cylinder g , the radial openings $h^2 h^2$ which coincide with the openings $e^2 e^2$ in the upper disk e , and the upwardly-extending annular flange h^3 in which are the notches $h^4 h^4$ on a line with the openings $h^2 h^2$, as shown in Fig. 2. 80

The projections $f^4 f^4$ on the ends of the hoppers extend through recesses in the disks d and e and hold the hoppers in position for the open ends of the hoppers to coincide with the openings $d^2 d^2$ and $h^2 h^2$ in the disks, and the disks, hoppers, glass cylinder and retaining cap are all secured together by the bolts $h^5 h^5$ which are headed on the under side of the lower disk d and extend upwards between the hoppers and through the upper disk e and the retaining ring h , as shown in Figs. 3 and 4. 90

The top i has the annular lip i' , the hollow central cone-shaped extension i^2 in which is the hub i^3 for supporting the top i on the upper end of the central column b and the vertical coin slot i^4 in a position to coincide with the upper end c^3 of the coin chute c , as shown in Figs. 1 and 4. 100

The hoppers $f f$ are each filled with a different style of collar button by removing the top i , holding the buttons in a position for the heads to enter the hoppers and the shanks to extend through the slots in the hoppers, and dropping the buttons through the openings $h^2 h^2$ in the cylinder retaining cap h and the openings $e^2 e^2$ in the upper disk into the hoppers where they are held by the notched fingers $f^{13} f^{13}$ on the operating levers $f^{12} f^{12}$. The different styles of buttons can now be easily seen by the buyer through the glass cylinder g and present a very attractive 110 display. 115

In the operation of my improved automatic vending machine the buyer grasps one of the knobs d^4 and revolves the disks d and e , the hoppers $f f$, the glass cylinder g , and the cylinder retaining cap h around the central column b until the style of collar button wanted is in front or over the delivery compartment a^2 . The spring actuated ball stop a^8 now snaps into one of the openings d^2 in the lower disk d and holds the hopper under spring tension in its delivery position, as shown in Figs. 1 and 3. The delivery position of a hopper unlocks the coin slot i^4 by bringing a notch h^4 in the cylinder retaining 120 125 130

cap h under the curved upper end c^3 of the coin chute c . The buyer now enters a coin in the coin slot i^4 . The peripheral edge of the coin engages with the upper edge of the 5 coin slot and the bottom c^2 of the coin chute c , as shown in broken lines in Fig. 1. A slight push on the coin in entering the coin chute now moves the coin chute downwards against the tension of the coiled spring b^{13} 10 into the position as shown in light broken lines in Fig. 4. This downward movement of the coin chute brings the outwardly-curved upper end c^3 of the chute into a notch h^4 in the cylinder retaining cap h , and the 15 lower end c^{12} of the slide c^{10} on the coin chute engages with the yoke f^{11} on the latch f^7 and moves the yoke downward. The downward movement of the yoke sets the latch f^7 by moving the hook-shaped lower end f^9 through 20 the aperture f^2 into the hopper and moving the notched finger f^{13} on the operating lever f^{12} outward from the hopper, the notch in the finger catching on the edge of the opening f^3 in the back of the hopper by the tension of 25 the spring f^{16} , which engaging with the upper end of the operating lever f^{12} , throws the lower end f^{14} of the operating lever toward the L-shaped end c^9 on the release lever c^5 , as shown in light broken lines in Fig. 4. The 30 buttons now drop in the hopper, the lower button being held by the hook-shaped lower end f^9 of the latch. The coin in dropping down the coin chute strikes the inner face of the column b and the release lever c^5 and 35 moves the release lever against the tension of the light coiled spring c^7 into the position as shown in heavy dotted lines in Fig. 4 and simultaneously the L-shaped end c^9 on the release lever strikes the end f^{14} of the operating lever f^{12} , and, assisted by the spring f^{16} , 40 throws the catch and operating lever back into their normal position, as shown in full lines in Figs. 1 and 4. The lower button is now released and drops into the delivery 45 compartment a^2 from which it is taken by the buyer and the coin drops through the release lever and hollow column into the coin receptacle a^9 , as shown in Fig. 1.

By the novel construction and arrangement of the parts of my improved automatic vending machine, only one size coin can be used for operating the machine. The size of the coin slot would prohibit the use of a larger coin and a smaller coin would pass 55 through the release lever c^5 without operating the same.

It is evident that the construction of the hoppers ff may be varied so that any small article of merchandise may be automatically 60 vended by the machine, without materially affecting the spirit of my invention.

Having thus described my invention, I claim as new and desire to secure by Letters Patent;

65 1. In a vending machine, the combination

of a base, a hollow central column supported on the base, a coin chute reciprocally supported in the central column, a series of merchandise hoppers rotatably secured around the central column, a latch supported on the merchandise hoppers adapted to first receive the merchandise and then deliver the same, means for rotating the merchandise hoppers around the central column, and mechanism on the coin chute adapted to operate the latch on the merchandise hoppers to receive the merchandise by the reciprocation of the coin chute and then deliver the merchandise on the dropping of the coin. 70 75 80 85 90 95 100

2. In a vending machine, the combination of a hollow base having an open delivery chamber and a coin receptacle, a hollow column centrally supported on the base, a coin chute in the hollow column, means for reciprocating the coin chute, a series of merchandise hoppers and a transparent cylinder rotatably secured around the hollow column, means for rotating the hoppers and cylinder around the column, mechanism on the coin chute adapted to engage in succession with mechanisms on the hoppers to automatically release an article of merchandise from a hopper on the dropping of a coin in the coin chute, means for automatically holding a hopper in its delivery position over the delivery compartment, a top in which is a coin slot, and means for locking the coin slot against the insertion of a coin when the hoppers are out of their delivery position, as described. 105 110 115 120 125 130

3. The combination with a vending machine of a hollow column b having the opening b' , the aperture b^2 and the slot b^3 , a coin chute c having the sides $c' c'$, the bottom c^2 , the curved upper end c^3 and the teats $c^4 c^4$, a release lever c^5 shaped to form a continuation of the coin chute c and pivotally secured at an angle to the lower end of the chute by the pin c^6 , a coiled spring c^7 connected with the coin chute and the release lever which is constructed to have the stop arms $c^8 c^8$ and the L-shaped end c^9 , the slide c^{10} secured to the coin chute by the pin c^6 , the coiled spring c^{13} secured to the slide c^{10} and to the column b , a series of merchandise hoppers ff each 115 hopper consisting of a flattened tube having the slot f' , the aperture f^2 , the opening f^3 , the projections $f^4 f^4$, the ears f^5 and f^6 , a latch f^7 pivotally secured to the ears f^5 by the pin f^8 and having the hook-shaped lower end f^9 , the ears f^{10} and the yoke f^{11} , an operating lever f^{12} having the notched finger f^{13} and the end f^{14} , a pin f^{15} for pivotally securing the operating lever f^{12} to the latch f^7 , and a flat spring f^{16} secured to the ears f^6 and bearing on the upper end of the operating lever f^{12} , as described.

4. A vending machine embodying a base, a cylinder, a cap thereon formed with radial openings, a revoluble merchandise hopper,

1
and means for discharging merchandise from said hoppers involving a coin actuated depressible coin chute adapted to enter said openings upon its depression.

5 5. A vending machine, embodying a central movable coin chute, a series of merchandise hoppers mounted to rotate thereabout, means operated by said chute and the dropping of a coin for discharging merchandise from said hoppers, and means for permitting movement of said coin chute when one of said hoppers is in discharge position.

10 6. A vending machine, embodying a tubular column, a depressible coin chute 15 therein, a spring held release lever pivoted to said chute, a slide carried by said chute, a spring connected to said slide and column, a plurality of merchandise hoppers, a latch adapted to be operated by said slide pivoted 20 to each hopper and having a part thereof extending in the hopper, and a spring held operating lever adapted to be operated by said release lever pivoted to each hopper and extending therein.

25 7. A vending machine embodying a central coin receiving chute, a series of rotatable merchandise hoppers disposed about said chute, means on the hoppers for ejecting the merchandise, means carried by said chute 30 for operating said ejecting means, means for locking said hoppers against movement, and means for preventing insertion of a coin into said chute when the hoppers are in unlocked position.

35 8. A vending machine embodying a base,

a revolute merchandise hopper, means for discharging merchandise from said hopper, coin-actuated depressible means for operating said last named means, and means whereby said depressible means may be operated 40 only at predetermined points.

9. A vending machine embodying a merchandise hopper, mechanism for discharging merchandise from said hopper, and a coin actuated depressible coin chute having its 45 lower end movable with respect to the major portion thereof, and formed to engage and operate said discharging mechanism.

10. A vending machine, embodying a merchandise hopper, mechanism for discharging merchandise from said hopper, and a coin actuated depressible coin chute having a pivoted spring pressed lower end adapted 50 to be moved outwardly by the dropping of a coin to actuate said discharging mechanism. 55

11. A vending machine, embodying a merchandise hopper, mechanism for discharging merchandise from said hopper, and a coin actuated depressible coin chute having a projection and a pivoted spring held part 60 for successive engagement with said discharging mechanism to actuate the same.

In testimony whereof I have signed my name to this specification in the presence of two subscribing witnesses.

HARRY R. HOLBROOK.
